UNITED STATES PATENT OFFICE.

EDWARD A. DICKEY, OF WIRETON, PENNSYLVANIA, ASSIGNOR OF ONE-HALF TO
CHARLES A. DICKEY, OF NEW SHEFFIELD, PENNSYLVANIA.

STARTING MECHANISM FOR ENGINES.

1,409,681.

Specification of Letters Patent. Patented Mar. 14, 1922.

Application filed June 28, 1920. Serial No. 392,400.

To all whom it may concern:

Be it known that I, EDWARD A. DICKEY, a citizen of the United States, residing at Wireton, in the county of Allegheny and State of Pennsylvania, have invented certain new and useful Improvements in Starting Mechanism for Engines, of which the following is a specification.

My invention refers to improvements in starting mechanism for engines, and more particularly for internal explosion engines as used on automobiles or power driven vehicles. It has in view to provide a simple, effective, and economical device for the purpose of utilizing the power of an electric motor to turn over the fly wheel and main shaft of the engine in starting.

The invention utilizes an actuating pinion of the starting motor and shifting mechanism for thrusting the teeth of the pinion lengthwise into mesh with a gear on the fly wheel or main shaft, and for effecting closing of the circuit to the starting motor after the pinion has been thrust into mesh, utilizing an initial low pressure current by means of intervening resistance, a special contact switch for subsequently giving the full current to the motor, means for retracting the pinion after starting, and various details of construction and operation, as shall be more fully hereinafter described.

The invention is generally applicable to any standard automobile, motor boat, aeroplane, or other construction, or in fact, to any gas or other internal explosion engine, either movable or stationary.

In the drawings, illustrating one preferred embodiment of the invention as applied to an automobile of well known construction,

40 Fig. 1 is a view in sectional elevation showing a portion of the power equipment provided with my improvement;

Fig. 2 is a cross sectional detail view on the line II—II of Fig. 1, showing the thrust connection with the starter pinion;

Fig. 3 is an enlarged detail view of portions of the starting gears;

Fig. 4 is a sectional plan view of Fig. 1; and

50 Fig. 5 is an enlarged sectional detail view through the current switch on the line V—V of Fig. 3.

Referring to the drawings, 2 is the casing for the engine provided with the usual main shaft and fly wheel 4, with which is incor-

porated in any suitable way the starting gear 5. The engine case 2 is mounted in the usual manner upon the underframe of the machine, and is provided with the transmission shaft 6 extending rearwardly for ordinary connection with the driving axle gears.

The starting motor 7, of any suitable construction, is provided with a square or splined shaft 8 upon which is mounted the pinion 9 adapted to be thrust longitudinally of shaft 8 into and out of engagement with gear 5. The engaging ends of the teeth of pinion 9 and gear 5 are preferably beveled as shown, to facilitate easy engagement in thrusting the pinion 9 into mesh. Pinion 9 is provided with a hub 10 having an annular groove 11 which is engaged by a thrust clevis or fork 12 made integral or rigidly connected with a thrust shaft 13. Shaft 13 extends through the end 14 of a suitable enclosing casing for pinion 9 and its shifting mechanism, which casing is incorporated with the mounting of the starter 7 and of the main case 2 so as to maintain the parts in rigid operative relation. Shift rod 13 extends rearwardly and is slidably engaged by a terminal abutment 15 of connecting rod 16, which in turn is actuated by lever arm 17 of rock shaft 18 mounted in suitable bearings below the floor 19 of the car.

A retracting spring 20 for thrust rod 13 bears by one end against the end of casing 14 and by its other end against washer 21 and a cotter pin 22 or other abutment fixedly connected with shaft 13. By means of spring 20, the pinion 9 is retracted from engagement with gear 5, after being pushed into gear and when the engine is in operation. A spring 23 of somewhat greater strength than spring 20 is interposed between a washer 24 and abutment 22 at one end and against the pressing abutment 15 at its other end.

An operating button 25 at the upper end of a thrust rod 26 is located sufficiently above floor 19 to be in convenient position after being pressed downwardly by the foot of an operator, and rod 26 is pivotally connected with an operating lever 27 of rock shaft 18.

A represents a switch device, shown in section in Fig. 4, by means of which energizing current is transmitted from battery B to the starting motor 7. At the commence-

ment of the operation, it is desirable that the starting current shall be modified as to its strength by means of a resistance 28 interposed in branch line 3 between a terminal 5 contact 29 and the main circuit connection 30 leading to one side of the motor 7. A companion contact 31 with contact 27 is similarly mounted within a suitable casing 32, and contacts 29 and 31 are adapted to 10 be simultaneously closed through a leaf spring contact 33 mounted upon the end of a thrust pin 34 in an extension 35 of the casing. Thrust pin 34 is provided with a terminal cap 36 and a retracting spring 37, 15 by which the thrust pin and contact spring may be depressed for starting the motor, and then retracted.

An additional contact 38 slightly below the general contacting zone of the primary 20 contacts 29 and 31, is connected with the main lead wire 30, the circuit being closed by connection 39 from the other side of battery B to the ground. After making the initial circuit through contacts 29 and 31, 25 for slow initial action of motor 7, further depression of stem 34 will supply the full current to the motor through contacts 31, 33 and 38, as will be readily understood.

An additional lever arm 40 on rock shaft 30 18 is located within operative reach of terminal 36 of the switch, with sufficient lost motion travel to ensure the thrusting of pinion 9 into mesh with gear 5 prior to the time the initial current is transmitted, further pressure upon stem 26 ensuring full 35 engagement of the gears prior to or simultaneously with the transmission to the starting motor 7 of the full current. Release of pressure upon button 25 effects opening of the 40 circuit assisted by lifting action of spring 41 and automatic retraction of pinion 9 from gear 5, upon the starting of the engine, so that the device is automatic in operation and independent of any subsequent voluntary 45 action by the operator.

The invention may be variously changed or modified in detail construction to adapt it to various installations or mounting of the engine or its equipment without departing 50 from the scope of the following claims.

What I claim is:

1. In combination with a starting motor having a slidably mounted pinion, a thrust rod in operative engagement with the pinion, a retracting spring and a pushing spring 55 engaging an abutment on the thrust rod, a switch in circuit with the motor, and lever mechanism adapted to actuate the thrust rod and the switch successively by continuous movement.

2. In combination with a starting motor having a slidably mounted pinion, a thrust rod in operative engagement with the pinion, a retracting spring and a pushing spring 60 engaging an abutment on the thrust rod, a

switch in circuit with the motor, and lever mechanism having a common rock shaft, a foot-pressed rod, a connection to the thrust rod, and an arm for the switch adapted to make engagement therewith to actuate it 70 after motion is imparted to the motor pinion.

3. In combination with a starting motor having a driving shaft and a slidably mounted pinion thereon; a thrust rod engaging the pinion, a retracting spring and a pressure spring each engaging an abutment on the thrust rod, a shifting arm directly engaging the pressure spring and slidably engaging the thrust rod, and lever mechanism connected with the shifting arm. 75

4. In combination with a starting motor having a driving shaft and a slidably mounted pinion thereon; a thrust rod engaging the pinion, a retracting spring and a pressure spring each engaging an abutment on the thrust rod, a shifting arm directly engaging the pressure spring and slidably engaging the thrust rod, a circuit for the motor embodying a switch, and lever mechanism connected with the shifting arm adapted to 80 first move the shifting arm and to then transmit movement to the switch.

5. In combination with a starting motor having a driving shaft and a slidably mounted pinion thereon; a thrust rod engaging the pinion, a retracting spring and a pressure spring each engaging an abutment on the thrust rod, a shifting arm directly engaging the pressure spring and slidably engaging the thrust rod, a circuit for the motor embodying a switch, a plurality of circuit contacts therein and a corresponding plurality of circuit lines leading to the motor embodying a resistance, and lever mechanism connected with the shifting arm adapted to 100 first move the shifting arm and to then transmit movement to the switch to actuate it progressively after the pinion thrusting mechanism has been actuated.

6. The combination with a starting motor having a slidably mounted pinion, a thrust rod having an abutment thereon, in operative engagement with the pinion, a retracting spring and a pushing spring engaging said abutment on the thrust rod, a shifting arm engaging the pushing spring, a rock shaft, means for operating the rock shaft, a lever on said rock shaft connecting with the shifting arm, and a switch operating lever on said rock shaft. 110

7. The combination with a starting motor having a slidably mounted pinion, a thrust rod having an abutment thereon, in operative engagement with the pinion, a retracting spring and a pushing spring engaging 115 said abutment on the thrust rod, a shifting arm engaging the pushing spring, a rock shaft, means for operating the rock shaft, a lever on said rock shaft connecting with the shifting arm, a switch operating lever 120

125

- on said rock shaft, and a switch controlling the operation of said motor positioned to be actuated by said lever after the thrust rod has moved said pinion into operative position, said pushing spring allowing for the further movement of the rock shaft.
8. The combination with a motor having a reciprocably movable pinion, of means for effecting the movement thereof comprising
- 10 a thrust rod having means thereon engaging the pinion to move it, an abutment on said rod, a pressure spring and a retracting spring engaging said abutment, a reciprocable shifting rod having means for engaging
- 15 the pressure spring, a rock arm for effecting the reciprocation of said shifting rod, and an operating means for moving the rock arm, said pressure spring providing a yieldable connection for transmitting motion from the shifting rod to the thrust rod,
- 20 motion from the shifting rod to the thrust rod.

9. The combination with a motor having a reciprocably movable pinion, of means for effecting the movement thereof comprising a thrust rod having means thereon engaging 25 the pinion to move it, an abutment on said rod, a pressure spring and a retracting spring engaging said abutment, a reciprocable shifting rod having means for engaging the pressure spring, a rock arm for effecting 30 the reciprocation of said shifting rod, an operating means for moving the rock arm, said pressure spring providing a yieldable connection for transmitting motion from the shifting rod to the thrust rod, 35 a second rock arm actuated from said operating means, and a switch adapted to be actuated by said rock arm.

In testimony whereof I hereunto affix my signature.

EDWARD A. DICKEY.
